SEWING MACHINE FOR COMFORTABLES
AND SIMILAR ARTICLES

Judson L. Miller, New York, N. Y.

Application June 22, 1932, Serial No. 618,690

9 Claims. (Cl. 112—117)

This invention relates to sewing machines and more particularly to sewing machines for sewing comfortables, quilts and similar articles. Certain features of the invention however are not limited to machines for sewing this particular kind of work but may be embodied in machines for sewing work of other kinds.

As is well known to those skilled in the art, comfortables and quilts and other bed coverings of this general character, each usually comprises one or more layers of woven fabric on each side thereof forming covers, and a relatively thick layer of cotton, wool or other padding material located between said covers. It has been common practice to stitch one or more seams each in an ornamental design through the fabric covers and the padding material to hold the padding material in place between the said covers. These ornamental seams add greatly to the attractive appearance of the comfortable or quilt.

In sewing such seams by hand, it has been quite general practice to sew each seam in an undulatory or wavelike form. That is, the seam, while following a certain pattern, has relatively short undulations or waves extending in directions transverse to the general line of the seam. This wavelike formation of the seams renders the design much more ornamental and attractive in appearance. As far as applicant is aware, no machine has been produced upon which seams having such undulations or waves can be sewn. The sewing of seams of this character by hand is expensive and adds considerably to the cost of the comfortable or quilt.

The primary object of the present invention is to produce a machine by which a seam may be sewn in any desired formation or design, and at the same time, the seam may be formed with undulations or waves extending in directions transverse to the general line of the seam.

Another object of the invention is to produce a machine adapted to sew a seam in an undulatory or wavelike formation in which the form of the undulations or waves may be readily varied.

With the above and other objects in view, the invention consists in a sewing machine embodying the novel and improved features herein-after described and particularly pointed out in the claims.

One feature of the invention consists in the provision of means for relatively vibrating the sewing mechanism and the work in directions transverse to the general line of feed.

Another feature of the invention consists in the provision of mechanisms respectively for relatively vibrating the work and the sewing mechanism in two different directions transverse to each other. These mechanisms are preferably arranged so that they may be thrown into and out of operation alternatively. In the form of

the invention shown, these mechanisms are constructed so that they may be thrown into and out of operation alternatively and that they may both be thrown into operation at the same time. When both mechanisms are in operation, a compound relative movement is imparted to the work and the sewing mechanism, the nature of which will depend on the timed relation of the two mechanisms. Either one or both mechanisms may be provided with means by which the timed relations of the two mechanisms may be adjusted. One or both of said mechanisms also may have provisions for adjustment to adjust the amplitude of the relative vibrating movement.

The above and other features of the invention will be clearly understood from the accompanying drawings illustrating the invention in its preferred form and the following detailed description of the constructions therein shown. It is to be understood however that the invention is not limited to the particular machine or to the particular construction and arrangement of parts of the illustrated embodiment of the invention, but that the construction shown is merely illustrative of the invention and that the invention may be embodied in many other forms within the scope of the claims.

In the drawings—

Fig. 1 is a view in side elevation of a machine embodying the invention;

Fig. 2 is a view in front elevation of the machine;

Fig. 3 is a sectional view of the machine taken substantially on the line 3—3 of Fig. 1;

Fig. 4 is a detail view illustrating a guide construction for one of the work carrying tables or frames; and

Figs. 5, 6, and 7 are detail views illustrating seam formations which may be sewn on the machine.

In the form of the invention illustrated in the drawings of this application, the machine is provided with a sewing mechanism of a suitable type for sewing comfortables and quilts. The sewing mechanism comprises a head indicated at 2 upon which are mounted the needle and presser foot mechanisms. This head is secured upon a hollow rod or bar 4 extending laterally of the machine. The sewing machine also comprises the underframe 6 upon which are mounted the devices arranged to operate below the work and co-operating with the needle in the formation of the stitches. This underframe is mounted upon a hollow supporting rod or bar 8 indicated at 8 extending laterally of the machine substantially parallel with the rod 4.

The quilt or comfortable is supported upon an upper carriage indicated as a whole at 10. This carriage is provided with a lower framework 12.

to which are secured uprights 14. To the upper ends of these uprights are attached the laterally extending bars 16 and to these bars are attached the ends of the clamp-carrying bars 18. 5 Upon the bars 18 are mounted the clamps 20 within which are inserted the margins of the quilt or comfortable to support the same in sewing position.

The carriage 10 is mounted so that it may 10 move freely laterally and forwardly and rearwardly in a horizontal plane to cause the stitch-forming mechanism to sew along any given pattern on a quilt or comfortable held in the work-holding clamps 20. The carriage 10 is also 15 mounted so that it may be vibrated forwardly and rearwardly and/or laterally to cause the stitch-forming mechanism to follow an undulatory or wavelike path in sewing the seam.

The carriage 10 is mounted for lateral vibrating movement upon rails 22 and to this end is 20 provided with guide members 24 of T-shaped cross section secured to the underside thereof and engaging respectively in laterally extending grooved tracks 26 secured respectively to the 25 upper sides of the rails 22. The rails 22 in turn are mounted for forward and rearward vibrating movement upon a second carriage 28. To this end the rails 22 are each provided with 30 guide members 30 also T-shaped in cross section and respectively located adjacent the ends of the rail which engage in grooves in forwardly and rearwardly extending track members 32 secured to the upper side of the carriage 28. The 35 downwardly projecting rib on each of the guide members 30 is preferably provided with recesses 34 and anti-friction rolls 36 are interposed between said guide member and the corresponding track 32, these rolls engaging in the recesses 34 as shown in Fig. 4.

The carriage 28 is mounted so that it may be 40 moved freely forwardly, rearwardly and laterally in a horizontal plane so that the required movements may be imparted to the comfortable in sewing any desired pattern upon the same. 45 As shown in the drawings, the carriage 28 is provided with wheels 38 respectively mounted upon wheel-carrying brackets 40 secured to the underside of the carriage, and these wheels engage tracks 42 secured to the upper side of a 50 third carriage 44 and extending laterally of the machine. The carriage 44 is provided with wheels 46 mounted upon wheel-brackets 48 secured to the underside of the carriage and these wheels engage tracks 50 supported upon any suitable stationary foundation and extending forwardly and rearwardly of the machine.

In order to enable the operator to move the carriage 28 in any desired direction in a horizontal plane during the sewing operation, the carriage is provided with a hand rod 52 mounted 60 upon bars 54 extending obliquely upwardly from the side of the carriage. This hand rod is arranged to be grasped by the operator and the carriage is moved forwardly and rearwardly and laterally in the desired directions by the manipulation of this hand rod. The movements thus imparted to the carriage by the operator feed the work past the stitch-forming mechanism and move the work to cause the seam to be 65 sewn in the desired pattern.

In the present construction a pattern plate 56 is mounted upon the upper side of the carriage 28. This pattern plate is formed with guide grooves 58 in which is engaged a guide roller 60 70 carried at the lower end of a rod 62 mounted to

slide vertically in suitable guides in a depending portion of the underframe 6 of the sewing mechanism. The engagement of the guide roller 60 with one of the guide grooves 58 determines the pattern followed by the sewing mechanism with relation to the work in sewing a seam. The carriage 28 is moved forwardly and rearwardly and laterally to carry the guide roll 60 through the various portions of the guide groove in which it engages by the manipulation 10 of the hand rod 52, and the movement of the carriage, of course, imparts corresponding movements to the work held in the work-holding clamps.

The mechanism for imparting forward and 15 rearward vibrating movements to the carriage 10 during the sewing operation comprises a shaft 64 mounted in suitable bearings 66 on the carriage 28. Upon the ends of this shaft are mounted 20 crank disks 68 each carrying a crank 70 connected by a pitman 72 with one end of the forward rail 22 which carries the forward track 26. Each of the cranks 70 is adjustable toward and from the axis of the shaft 64 to adjust the amplitude of the vibratory movements imparted to 25 the carriage 10. To this end each crank is adjustably mounted in a diametrical groove 74 formed in the corresponding crank disk (see Fig. 1). The mechanism for driving shaft 64 comprises a gear 76 fixed to the shaft and meshing 30 with a gear 78 loosely mounted upon a counter-shaft 80 which is arranged to rotate in bearings 82 carried by the carriage 28. Fixed to the gear 78 is a clutch member or sleeve 84 having a clutch recess in which engages a correspondingly-shaped 35 tooth or projection formed on the clutch member 86 mounted on the shaft 80 to rotate with the shaft, but slideable on the shaft, to carry the same into and out of engagement with the clutch member 84. To the shaft 80 is secured a pulley 88 40 which is connected by a belt 90 with a pulley 92 secured to one end of the armature shaft of an electric motor 94.

The engagement of the clutch member 86 with the clutch member 84 is controlled by a lever 96 45 pivoted at 98 on the carriage 28 and carrying at its free end pins or rolls engaging in a groove in the clutch member 86. Electrically operated mechanism controlled by the operator is preferably employed for shifting the lever 96 in both 50 directions to engage and disengage the clutch members. The lever is shifted in a direction to engage the clutch members by means of a solenoid 100, the core of which is connected by a link 102 with the lever. The lever is shifted in a 55 direction to disengage the clutch members by means of a solenoid 104, the core of which is connected by a link 106 with the lever.

The mechanism for imparting lateral vibrating movements to the carriage 10 comprises a 60 shaft 108 mounted in bearings 110 carried by the carriage 28. Upon the ends of this shaft are mounted crank disks 112 each carrying a crank 114 which is connected by a pitman 116 with the carriage 10. Each of the cranks 114 is mounted 65 on the corresponding crank disk for adjustment toward and from the axis of the shaft 108, each crank disk having a diametrical groove 118 (see Fig. 2) in which the corresponding crank is adjustably mounted.

The mechanism for driving the shaft 108 comprises a bevel gear 120 fixed to the shaft, and a bevel gear 122 loosely mounted on the counter-shaft 80 and meshing with said gear 120. To the gear 122 is fixed a clutch member 124 having an 70

angular clutch recess in which engages a correspondingly shaped tooth formed on a clutch member 126 mounted on the shaft 80 for rotary movement with the shaft but movable longitudinally of the shaft to carry the same into and out of engagement with the clutch member 124. The position of the clutch member 126 on the shaft is controlled by a shifting lever 128 pivoted at 130 on the carriage 28 and carrying at its free end rolls or pins engaging in a groove in the clutch member 126.

Electrically actuated mechanism controlled by the operator is also provided for moving the lever 128 to carry the clutch member 126 into and out of engagement with the clutch member 124. The lever 128 is moved in a direction to carry the clutch member 126 into engagement with the clutch member 124 by means of a solenoid 132 connected by a link 134 with the lever 128. The lever 128 is moved in a direction to disengage the clutch member 126 from the clutch member 124 by means of a solenoid 136 connected by a link 138 with the lever 128.

The electrical circuits for the motor 94 and for the solenoids 100, 104, 132 and 136 are shown diagrammatically in Fig. 3. The circuit for the motor 94 comprises a conductor 140 connecting the motor with one of the main circuit terminals 142 and a conductor 144 connecting the motor with one of the terminals of a switch 146 for opening and closing the motor circuit. The other terminal of this switch is connected by a conductor 148 with the main circuit terminal 150. The solenoid 100 is connected by a conductor 152 with one of the terminals of a switch 154, the other terminal of which is connected by a conductor 158 with the conductor 144. The solenoid 100 is also connected by a conductor 160 with the conductor 140. The solenoid 104 is connected by a conductor 162 with one of the terminals of a switch 164, the other terminal of which is connected with the conductor 158. The solenoid 104 is also connected by a conductor 168 with the conductor 140. The solenoid 132 is connected by a conductor 170 with one of the terminals of a switch 172, the other terminal of which is connected with the conductor 158. The solenoid 132 is also connected by a conductor 176 with the conductor 140. The solenoid 136 is connected by a conductor 178 with one of the terminals of a switch 180, the other terminal of which is connected with the conductor 158. The solenoid 136 is also connected by a conductor 182 with the conductor 140.

The switches 154, 164, 172 and 180 are all preferably of the push button type and are also preferably mounted on the hand rod 52 by which the carriage 28 is moved by the operator. By the actuation of certain of these switches the mechanism for imparting forward and rearward vibrating movements to the carriage 28 and the mechanism for imparting lateral vibrating movements to said carriage may be thrown into and out of operation alternatively, or both mechanisms may be thrown into or out of operation at the same time. Thus when the guide roll 60 is engaged in a portion of one of the grooves 58, the direction of which is mainly forward and rearward of the machine, the mechanism for imparting the lateral vibrating movements to the carriage 28 may be thrown into operation by the actuation of the switch 172. When the roll 60 arrives at a portion of the groove the direction of which is mainly transverse to the machine, the mechanism for imparting the lateral vibrating

movements may be thrown out of operation by the actuation of the push button 180 and the mechanism for imparting the forward and rearward vibrating movements may be thrown into operation by the actuation of the push button 154. When the roll 60 again arrives at a portion of the groove the direction of which is mainly forward and rearward of the machine, the mechanism for imparting forward and rearward vibrating movements may be thrown out of operation by the actuation of the switch 164 and the mechanism for imparting the lateral vibrating movements may be again thrown into operation by the actuation of the switch 172.

When it is desired to throw both the mechanism for imparting the lateral vibrating movements and the mechanism for imparting the forward and rearward vibrating movements to the carriage 10 into operation at the same time, this may be done by closing both the switches 172 and 154. When both these mechanisms are in operation, compound relative movements will be imparted to the carriage 28. The paths of these movements will depend upon the timed relation of the two mechanisms.

It will be noted from an inspection of Fig. 3 that each of the clutch members 88 and 126 is provided with a single projection or tooth and that the respective co-operating clutch members 84 and 124 are each provided with a single recess 30 for receiving the said projection. Thus when both the clutches are engaged the mechanism for imparting the forward and rearward vibrating movements to the carriage and the mechanism for imparting the lateral vibrating movements 35 to said carriage will operate in definite timed relation to each other. Provision is made for adjusting this timed relation of the two mechanisms. To this end each of the crank disks 68 is mounted upon a sleeve 184 engaging in and projecting through the bearing 66. This sleeve is secured to the shaft 64 by means of a set screw 186. By loosening these set screws each of the crank disks 68 may be adjusted about the axis of the shaft 64. A similar construction, if desired, 45 may be provided for connecting each of the crank disks 112 with the shaft 108.

In order to accommodate the forward and rearward vibrating movements of the carriage 10, each of the pitmen 116 is connected somewhat 50 loosely to the crank 114 at its lower end and its upper end is connected somewhat loosely to a bolt or pin 188 secured in the carriage. Coiled springs 190 are interposed respectively between the pitman and the head of the pin and between 55 the pitman and the carriage to maintain the pitman normally in an intermediate position longitudinally of the projecting portion of the pin. This construction however allows the pin to move through the hole in the pitman during the forward and rearward reciprocating movements of the carriage 10. A similar construction, if desired, may be provided for connecting the respective pitmen 72 with the cranks 10 and with the forward rail 22.

It is to be noted that the switch 146 controls both the circuit for the motor 94 and the circuits for the solenoids 100, 104, 132 and 136. Thus when the switch 146 is open, the motor is out of operation and none of the solenoids can be actuated to shift the movable members of the clutches which control the vibrating movements.

Figures 5, 6 and 7 show seams which may be sewn upon the present machine. Figure 5 shows seams 192 and 194 in which the vibrating mecha-

nisms give a simple wavelike form to the seam. Figure 6 shows seams 196 and 198 also having a simple wavelike form, differing from those shown in Figure 5 in the height and pitch of the waves. 5 Figure 7 shows seams 200 and 202 in which a series of loops have been formed in each seam by the action of the vibrating mechanisms.

It is to be understood that the invention is not limited to machines of the particular type 10 shown in the drawings of this application or to the particular construction and arrangement of parts of this machine, but that the invention may be embodied in other types of machines and in other forms within the scope of the claims.

15 Having explained the nature and object of the invention and having specifically described a machine embodying the invention in its preferred form, what is claimed is:

1. A sewing machine having in combination, 20 a work carrier, means for supporting the carrier for movement in any direction in a horizontal plane to permit the sewing mechanism to follow any desired pattern on the work, mechanism for imparting relatively short horizontal 25 vibrating movements to the carrier in one direction independent of its pattern describing movement, mechanism for imparting relatively short horizontal vibrating movements to the carrier in another direction transverse to the first vibrating 30 movements and independent of the pattern movement and devices by which the respective vibrating mechanisms may be thrown into and out of operation alternatively.

2. A sewing mechanism having in combination, 35 a work carrier mounted for movement in any direction in a horizontal plane to permit the sewing mechanism to follow any desired pattern on the work, mechanism for imparting relatively short horizontal vibrating movements to the carrier in one direction independent of the pattern 40 describing movement, mechanism for imparting relatively short horizontal vibrating movements to the carrier in another direction transverse to the first vibrating movements and independent of the pattern 45 describing movement and devices by which both said vibrating mechanisms may be thrown into operation at the same time.

3. A sewing machine having in combination, 50 a work carrier, means for supporting the carrier for movement in any direction in a horizontal plane to permit the sewing mechanism to follow any desired pattern on the work, mechanism for imparting relatively short horizontal vibrating movements to the carrier in one direction independent of its pattern 55 describing movement, mechanism for imparting relatively short horizontal vibrating movements to the carrier in another direction transverse to the first vibrating movements and independent of the pattern movement and devices by which both said vibrating 60 mechanisms may be thrown into and out of operation alternatively or both may be thrown into operation at the same time.

4. A sewing mechanism having in combination, 65 a work carrier mounted for movement in any direction in a horizontal plane to permit the sewing mechanism to follow any desired pattern on the work, mechanism for imparting relatively short horizontal vibrating movements to the carrier in one direction independent of the pattern 70 describing movement, and mechanism for imparting relatively short horizontal vibrating

movements to the carrier independent of the pattern describing movements and in definite timed relation to the first vibrating movements.

5. A sewing mechanism having in combination, 5 a work carrier mounted for movement in any direction in a horizontal plane to permit the sewing mechanism to follow any desired pattern on the work, mechanism for imparting relatively short horizontal vibrating movements to the carrier in one direction independent of the pattern 10 describing movement, and mechanism for imparting relatively short horizontal vibrating movements to the carrier independent of the pattern describing movements and in definite timed relation to the first vibrating movements, one 15 of said mechanisms having provision for adjustment to vary said timed relation.

6. A sewing machine having in combination a work carrier, means for supporting the carrier for movement in any direction in a horizontal 20 plane, sewing mechanism, means for guiding the work carrier to cause the sewing mechanism to describe a predetermined pattern on the work and means other than said guiding mechanism for imparting relatively short vibrations to the work 25 carrier in directions transverse to the line of feed to cause the sewing mechanism to sew a wavelike seam.

7. A sewing machine having in combination a work carrier, means for supporting the carrier 30 for movement in any direction in a horizontal plane, sewing mechanism, a pattern fixed to the work carrier for movement with the work, a fixed 35 guide for engaging the pattern to guide the work carrier and cause the sewing mechanism to describe a predetermined pattern on the work and means other than said guiding mechanism for imparting relatively short vibrations to the work carrier in directions transverse to the line of feed to cause the sewing mechanism to sew a wavelike 40 seam.

8. A sewing machine having in combination a sewing mechanism, a support mounted for linear movement, a second support mounted on the first for movement in a line transverse to the line of 45 movement of the first support, a work carrier mounted on the second support for vibrating movement relatively thereto, a pattern fixed to the second support, a guide for engaging the pattern to guide the work carrier and cause the sewing mechanism to follow the pattern, and additional means for vibrating the carrier with relation to said second support in directions transverse to the movement of the work carrier as determined by said pattern to thereby cause the 55 sewing mechanism to sew a wavelike seam.

9. A sewing machine having in combination a sewing mechanism, a support mounted for linear movement, a second support mounted on the first for movement in a line transverse to the line of 60 movement of the first support, a work carrier mounted on the second support for movement relatively thereto in a horizontal plane, a pattern fixed to the second support, a guide for engaging the pattern to guide the work carrier and cause 65 the sewing mechanism to follow the pattern, and additional means for vibrating the carrier with relation to said second support in directions transverse to the movement of the work carrier as determined by said pattern to thereby cause the 70 sewing mechanism to sew a wavelike seam.

JUDSON L. MILLER.
